UNITED STATES PATENT OFFICE

2,507,158

MOLD JACKET

Russell J. Hines, Lakewood, Ohio, assignor to The Hines Flask Co., Cleveland, Ohio, a corporation of Ohio.

Application December 23, 1948, Serial No. 66,869

2 Claims. (Cl. 22—112)

1

This invention relates to a foundry jacket adapted to surround a sand mold and hold it in shape during the pouring of the molten metal to insure a proper casting. One of the objects of the invention is to provide such a jacket so arranged and constructed that it will hold the mold very accurately and will not become unduly hot in use and will be convenient for handling both before and after the cast has been made. Another object of my invention is to provide simple means for holding a plurality of jackets, one mounted on another, for encasing an extra deep mold. Cheapness of construction is also a feature of my jacket.

In common with other mold jackets, my jacket comprises four panels held together at the corners. I have provided, however, novel and effective means for securing the corners rigidly to each other and at the same time allowing for the ready separation of the panels at the corners for convenience in shipping or for replacement of any damaged panel.

My improved jacket is illustrated in the accompanying drawings and is hereinafter fully explained and the novel features are summarized in the claims.

In the drawings, Fig. 1 is a side elevation of the complete jacket; Fig. 2 is a bottom plan thereof; Fig. 3 is a vertical section, as indicated by the line 3—3 of Fig. 1 showing also parts of the adjacent panel; Fig. 4 is an enlarged horizontal cross section through any of the four corners of the jacket; Fig. 5 is a side elevation partly broken away of a plurality of my jackets mounted one above the other to hold a deeper mold; Fig. 6 is a vertical section in a plane indicated by the line 6—6 on Fig. 5.

Each panel of my jacket comprises an outer cast metal member 10 of open grill work and an impervious heat resisting lining 20. The grill work of the body 10 preferably has a sort of lattice formation, as shown in Figs. 1 and 3, providing ribs 11 of ample strength while leaving large open spaces 12. The inner face of this member 10 is perfectly smooth. Secured to this inner face is a continuous sheet of strong heat-resisting material 20. This sheet is preferably of a composition of asbestos and cement united by pressure into a smooth relatively hard slab. This slab is rigidly and permanently secured to the outer member 10, as for instance by tubular rivets 30 which are countersunk in the lining to leave a perfectly flush interior, and extend through the frame member 10. The four panels are then secured together at the corners, by means about

2

to be described, providing a rectangular jacket. The open rib construction of the body members materially lightens the jacket while providing sufficient strength. It also enables a rapid radiation of such heat as passes through the heat-resisting lining.

Each frame member 10 is formed at its opposite ends with an outwardly projecting wing 13 preferably extending at an angle of about 135° to the side portions of the body member. Each of these wings is recessed at its inner face with a vertical channel 14. Registered openings are made through the adjacent wings through which extend bolts 40 carrying nuts 41. Between the wings and the endmost portions of the adjacent linings is a filler 50 which is snugly affixed, at least temporarily, to each of the adjacent frame members and their linings.

In manufacturing the jacket, each side member 20 of the body is cast, the inner face thereof is then machined to make a smooth plane, then the lining panel 20 is secured over this smooth face by the insertion and upsetting of the rivets 30. Then each of the side panels similarly made are clamped together about a forming block or jig having the exact outside dimension of the sand mold with which the jacket is to be used; then the nuts are tightened on the bolts firmly clamping the four side panels to the forming block, which is chamfered at the corners. Thus when the side panels are clamped about the block a space is left between the adjacent wings and the immediate adjacent portions of the liners. Then molten metal, as for instance aluminum, is cast in this space, the outer end of the space being blocked at the time.

The operation described produces the filler, shown at 50 in Figs. 2 and 4, and results in forming a rigid rectangular structure ready for use as a mold jacket, as shown in Fig. 2. I prefer to cast the filler 50 while the side panels are cold and free from soldering acid so that while the filler adheres with considerable firmness to both panels it may be readily detached from either of them by a mere hammer blow. This enables the ready separation of the four panels whenever desired, providing for convenient shipping, and also for replacement of any side should it become damaged.

I prefer to form each body member with a central laterally extending recess near the top, as indicated at 15 in which a U-shaped handle 16 may be pivotally mounted, the body having an inwardly projecting lug 17 behind the handle when it depends into the recess.

The provision in my jacket of the outer or grill member of each side panel and the stiff heat resisting lining enables a plurality of jackets to be surmounted one on the other and secured together as a unit by extending the same liner sheet continuously across two jackets. This provides a deeper jacket available for a deeper mold but still operable as a unit.

The construction just mentioned is illustrated in Figs. 5 and 6, which show two of the side grill members 10a and 10b one above the other, united by a lining member 20a which overlaps both grill members and is secured thereto by rivets 30a into the grill member 10a and rivets 30b into the grill member 10b. In these figures, the space below the liner 20a is occupied by a short liner 20b secured by the rivets 31b to the lower portion of the grill member 10b.

Figs. 5 and 6 show merely two of the jackets one above the other. If a greater number are employed, for instance, three, the liner 20b would be of sufficient length to extend below the grill member 10b and third grill member and would be riveted to it in the same manner as the liner 20a shown. If desired, however, a one-piece liner may be used in conjunction with a plurality of grill members instead of a plurality of liners.

There is a draft or incline in the inner surface of the side panels as is usual in the case of flasks. In the case of multiple jackets above described each lower grill member is of correspondingly larger dimensions so as to maintain a continuous incline on the inner face of the combined jacket as illustrated in Fig. 6.

It will be seen from the description given that I have provided in simple form a mold jacket which will have the requisite strength while being comparatively light to handle. The heat resisting lining materially reduces the heat which passes from the casting to the exterior of the jacket and open formation of the outer panel of the jacket provides for ready radiation of such heat. The resulting rapid radiation also has the decided advantage of keeping the jacket sides from warping due to the intense heat of the casting being poured. Cheapness of construction of the jacket is also a feature of my invention, as is the ability to readily separate the four sides of the jacket from each other whenever desired.

The ready separation of my jacket allows the insertion of shims between the cast filler members at the corners and the adjacent wings of the jacket, to enlarge the jacket from its original form whenever required. This is readily effected by loosening the retaining bolts at the corners and separating the jackets and inserting suitable shims having openings for the bolts to pass

through the filler member, shims and panel wings.

I claim:

1. A foundry jacket comprising a closed geometric space bounded by a plurality of panels, each panel comprising a body member having a liner, each liner comprising a sheet of heat resisting material contiguous with the entire surface adjacent said closed space, each body member having an outwardly extending oblique wing at its respective ends, each wing coacting in spaced abutting relation with another wing of an adjacent body member, a filler member extending continuously between the wings of adjacent body members and extending inwardly into the geometric space and having means overlapping the liners adjacent the ends of the panels, said filler member being snug against both body members but removable from at least one of them, and means interconnecting the two wings of adjacent panels and the interposed filler member.
2. A foundry jacket comprising a closed geometric space bounded by a plurality of side panels, each side panel comprising a body member of open grill work having a smooth face adjacent said closed space, a smooth continuous heat resisting sheet liner contiguous with said entire smooth face and riveted thereto, each body member having an outwardly extending oblique wing at its respective ends, each wing having a recess on its inner face, the end of the liner stopping short of the edge of said recess, each wing coacting in spaced abutting relation with a corresponding wing of an adjacent body member, a filler member continuously cast between adjacent wings, said filler member occupying the recesses in the wings and extending inwardly into the geometric space and having means overlapping the ends of the liners of adjacent body members, and bolts passing through the wings of adjacent body members and the filler member therebetween.
